FIGURE 1 is a perspective view of a girder embodying our new design, the view being taken generally from one end and the upper and outer sides thereof;

FIGURE 2 is another perspective view of a portion of the girder of FIGURE 1, but taken generally from one end and the upper and inner sides thereof;

FIGURE 3 is an end view taken from one end of the girder shown in FIGURE 1;

FIGURE 4 is an end view taken from the other end of the girder shown in FIGURE 1;

FIGURE 5 is a view from the outer side of a portion of the girder shown in FIGURE 1;

FIGURE 6 is a view from the inner side of a portion of the girder shown in FIGURE 1;

FIGURE 7 is a top view of the girder shown in FIGURE 1;

FIGURE 8 is a bottom view of the girder shown in FIGURE 1;

FIGURE 9 is a perspective view of a modified form of a girder embodying our new design, the view being taken generally from one end and the upper and outer sides thereof;

FIGURE 10 is another perspective view of a portion of the girder of FIGURE 9, but taken generally from one end and the upper and inner sides thereof;

FIGURE 11 is an end view taken from one end of the girder shown in FIGURE 9;

FIGURE 12 is an end view taken from the other end of the girder shown in FIGURE 9;

FIGURE 13 is a view from the outer side of a portion of the girder shown in FIGURE 9;

FIGURE 14 is a view from the inner side of a portion of the girder shown in FIGURE 9;

FIGURE 15 is a top view of the girder shown in FIGURE 9;

FIGURE 16 is a bottom view of the girder shown in FIGURE 9;

FIGURE 17 is a perspective view of a further modified form of a girder embodying our new design, the view being taken generally from one end and the upper and outer sides thereof;

FIGURE 18 is another perspective view of a portion of the girder of FIGURE 17, but taken generally from one end and the upper and inner sides thereof;

FIGURE 19 is an end view taken from one end of the girder shown in FIGURE 17;

FIGURE 20 is an end view taken from the other end of the girder shown in FIGURE 17;

FIGURE 21 is a view from the outer side of a portion of the girder shown in FIGURE 17;

FIGURE 22 is a view from the inner side of a portion of the girder shown in FIGURE 17;

FIGURE 23 is a top view of the girder shown in FIGURE 17;

FIGURE 24 is a bottom view of the girder shown in FIGURE 17;

FIGURE 25 is a perspective view of a still further modified form of a girder embodying our new design, the view being taken generally from one end and the upper and outer sides thereof;

FIGURE 26 is another perspective view of a portion of the girder of FIGURE 25, but taken generally from one end and the upper and inner sides thereof;

FIGURE 27 is an end view taken from one end of the girder shown in FIGURE 25;

FIGURE 28 is an end view taken from the other end of the girder shown in FIGURE 25;

FIGURE 29 is a view from the outer side of a portion of the girder shown in FIGURE 25;

FIGURE 30 is a view from the inner side of a portion of the girder shown in FIGURE 25;

FIGURE 31 is a top view of the girder shown in FIGURE 25;

FIGURE 32 is a bottom view of the girder shown in FIGURE 25.

The center of the girder in FIGURES 1, 9, 17, and 25 is broken away to indicate an article of indefinite length.

We claim:

The ornamental design for an overhead crane girder, substantially as shown and described.
